UNITED STATES PATENT OFFICE.

ELIJAH MORGAN, OF MORGANTOWN, VIRGINIA.

WASHING-MACHINE.

Specification of Letters Patent No. 12,518, dated March 13, 1855.

To all whom it may concern:

Be it known that I, ELIJAH MORGAN, of Morgantown, in the county of Monongalia and State of Virginia, have invented a new 5 and useful Improvement in Washing-Machines; and I do hereby declare that the following is a full, clear, and exact description of the same.

The nature of my invention consists in 10 suspending a reciprocating rubber between a yielding bar, and the wash board, in such manner that said wash board and bar may both have a vertical motion during the action of the rubber, and at the same time an 15 expansive action or motion due to an over- accumulation of the clothes between the rubber and the wash board.

To enable others skilled in the art to make and use my invention, I will proceed to de- 20 scribe its construction and operation, refer- ence being had to the accompanying draw- ings forming part of this specification, in which:—

Figure 1, is a longitudinal sectional ele- 25 vation of the machine. Fig. 2, is a top view of the same. Fig. 3, is an end sectional elevation of the same. Fig. 4, is a perspective view of an upper wash board furnished with one lid only.

Similar letters of reference in each of the 30 several figures indicate corresponding parts.

A, is the box of the machine; B, the lower wash board; C, upper wash board; c. c', lids of same; D, connecting bars of the 35 lower wash board; E, springs on the bars D; G, connecting straps between lower wash board and bars D; F, spring under the bottom of lower wash board; H, operating brake, h, pitman of same; I, supporting 40 arm; K, connecting rod; J, pivot of same; a, hinges of lids c. c'; b, pivot of the pitman; d, pins of bars D.

The lower wash board D, covers the entire 45 bottom of the washing box, one end only resting on the bottom of the same, the other end being supported by the elliptical spring F. The wash board B, is connected with the side bars D, above, by means of straps G, which unite with the extremities of springs 50 E, the latter being fastened to the bars. The other ends of the bars are attached to

the ends of the box by means of pins d, on which they move.

The upper wash board slides between the bars D, and lower wash board B; the bars 55 D, serving to confine the side frame pieces of the upper wash board. The articles to be washed are cleansed by placing them between the two wash boards, and moving the upper board back and forth over the lower 60 or stationary one.

In order to introduce the clothes conveniently between the boards, the lids c, c', are thrown up or opened as indicated by the red lines, Fig. 1. The pitman, it will be ob- 65 served, is attached to one of the lids, so that by raising the brake, the lid with which it is connected, opens. The other lid is raised by the hand, as seen. The blue color in Fig. 1, represents the clothes after having been 70 introduced between the boards, and the lids closed.

Reciprocating motion is communicated to the wash-board C, by the elevation or de- 75 pression of the brake H.

The surfaces of the wash boards, between which the clothes rest, are serrated in the usual manner.

When it is desirable, the upper wash board may have only one lid, as shown in 80 Fig. 4.

The springs E, and F, allow a yielding of the wash boards, which permits a variation of the bulk of the articles to be washed, while at the same time an even pres- 85 sure is maintained between them. The springs also relieve the articles between the boards, from the harshness of the rubbing process, and thereby prevent the possibility of rents or damage to cloths delicate of tex- 90 ture.

My improvement is at once, simple, cheap, effective, and in the highest degree effective. It requires but little power in its operation, and is adapted to the cleansing of all kinds 95 of fabrics. By its use, the operation of wash- ing in families, hotels, and other establish- ments, may be greatly abridged, and a cor- responding economy be effected, besides hav- ing the work much better done than it could 100 otherwise be.

Having thus fully described the nature of

my invention what I claim therein as new and desire to secure by Letters Patent is— Suspending a reciprocating rubber C, between the yielding bar D, and wash board B, in such manner that said wash board and bar may both have a vertical motion during the action of the rubber, and at the same time an expansive action or motion due to

an over accumulation of the clothes between the rubber, and the wash board, as described.

ELIJAH MORGAN.
